G. FORNACA

TWO-STROKE ENGINE OF THE OPPOSED PISTON TYPE

Filed Nov. 10, 1926

Fig. 1

Fig. 3

Inventor:

Guido Fornaca,
By *Henry G. Smith*,
Atty.

UNITED STATES PATENT OFFICE.

GUIDO FORNACA, OF TURIN, ITALY.

TWO-STROKE ENGINE OF THE OPPOSED-PISTON TYPE.

Application filed November 10, 1926, Serial No. 147,516, and in Italy November 17, 1925.

This invention relates to that type of two stroke internal combustion engine in which two pistons work in each cylinder, said pistons moving in opposite directions and being connected, by means of connecting rods, to two separate crank shafts; its object is to provide an improved engine of this type, more especially for aircraft, having its parts compactly arranged.

Accordingly, my invention consists of an engine of this type, characterized in that one end of the engine is provided with a casing in which is journalled the driven or propeller shaft, whereas its other end is provided with a superfeed compressor, said casing and said compressor constituting extensions of the cylinder group.

Preferably, the driven shaft has fixed thereon a toothed wheel in mesh with two pinions secured one on each of the crank shafts.

The compressor occupies the space between the magneto, oil pump, etc., and the body thereof constitutes a connecting means between the upper and the lower crank cases of the engine.

One constructional form of my improved engine is illustrated on the accompanying drawing.

Fig. 1 is a rear elevation of the engine. Fig. 2 is a side view, partly in section, on the line A—B of Fig. 1.

Fig. 3 is a section in the plane represented by the line C—D of Fig. 2.

Referring to the drawings, 1 denotes the lower crank case of the engine on which are mounted the cylinders 3 which are open at their ends and provided with admission openings 4, discharge openings 5 and sockets 6 for the sparking plugs. Upon the cylinders 3 is secured the upper crank case 1' similar to the crank case 1. Said crank cases are provided with an extension casing 2'. Journalled in bearings in the crank cases, 1, 1' are the two crank shafts 7, 7' to

which the opposed pistons 9 in each cylinder 3 are connected through connecting rods 8.

Each crank shaft is provided, at one of its ends, with a pinion 10 in mesh with a reducing gear wheel 11 secured on the driven or propeller shaft 12 that is journalled in the casing formed by the extension 2'.

The other ends of the crank shafts carry gear wheels 13 in mesh with gear wheels 16 on the vertical shaft 14 of a superfeed compressor 15 of the rotary type, said compressor forming an extension of the cylinder group. The gear wheel 13 of the shaft 7 also operates, through a pinion 17 and a reducing gear 18, the water pump 19 and the oil pump (not shown).

The shaft 7' is provided with a pinion 20 through which it operates the ignition magnetos 21.

Pipes 22 convey the compressed air from the compressor casing 15 to the carburetors 23.

What I claim is:

In an internal combustion engine with oppositely arranged pistons, the combination of two end casings forming chambers, a series of cylinders containing the pistons arranged parallel to and interposed between the end casings, crank casings at both ends of the cylinders extending over and closing both chambers, crank shafts arranged in the crank casings and extending into both chambers, compressor rotors for generating the scavenging and forced feed air disposed in one of the end chambers so that their axes lie parallel to those of the cylinders, bevel gears operatively connecting both crank shafts with one of said rotors, a driven shaft journalled in the other chamber parallel to the crank shafts, and reducing gears in the last named chamber operatively connecting the driven and crank shafts.

In testimony that I claim the foregoing as my invention I have signed my name.

GUIDO FORNACA.
